[57] CLAIM

The ornamental design for a wastebasket combined with lid, as shown and described.

DESCRIPTION

FIG. 1 is a top perspective view of a wastebasket combined with lid showing my new design;

FIG. 2 is a top plan view of FIG. 6;

FIG. 3 is a front elevational view of FIG. 6, the rear elevational view being a mirror image of that shown;

FIG. 4 is a side elevational view of FIG. 6, the opposite side elevational view being a mirror image of that shown;

FIG. 5 is a bottom plan view of FIG. 6;

FIG. 6 is a top perspective view of the wastebasket, the lid has been omitted to more clearly show the wastebasket;

FIG. 7 is a top plan view of FIG. 1;

FIG. 8 is a front elevational view of the lid, the rear elevational view being a mirror image of that shown, the wastebasket has been omitted for the convenience of illustration;

FIG. 9 is a side elevational view of the lid, the opposite side elevational view being a mirror image of that shown;

FIG. 10 is a bottom plan view of the lid;

FIG. 11 is a sectional view of the lid, taken along the line 11—11 of FIG. 9.
